UNITED STATES PATENT OFFICE.

HENRY BERGER, OF NEW YORK, N. Y.

DESIGN FOR CENTER-PIECE.

Specification forming part of Design No. 7,354, dated April 7, 1874; application filed March 27, 1874.
 [Term of Patent 14 years.]

E.

To all whom it may concern:

Be it known that I, HENRY BERGER, of the city, county, and State of New York, have invented a new and original Design for Center-Piece; and I do hereby declare the following to be a full, clear, and exact description thereof, which will enable those skilled in the art to make and use the same, reference being had to the accompanying drawing forming a part of this specification, which drawing shows a face view of my design.

This invention consists in the design of a central button surrounded by a circular ornamental collar, outside of which are sea-shells and a bead of alternate segments and angles, which is inclosed by a circular rim of alternate ram's-horn escutcheons and scrolls.

In the drawing, the letter A designates the central button of my design, which is of a circular shape, and is ornamented with arrowheads *a*. Encircling this button is a collar, B, which is ornamented with scallops and depressions, as shown. C are sea-shells located

around the collar B, and which are surrounded by a bead of alternate segments, D, and angles or rays E. Opposite the angles E, in the rim of the design, are ram's-horn escutcheons F, while opposite the segments D are scrolls G, supporting a leaf, *b*, in a spread condition. Said escutcheons and scrolls are interspersed with ornamental tracery or scroll-work *c*, the whole being of a circular shape or outline.

What I claim as new, and desire to secure by Letters Patent, is—

1. The combination of the shells C and collar B with the central button A, as shown and described.

2. The escutcheons F and scrolls G, in combination with the bead D E, shells C, collar B, and central button A, as shown and specified.

This specification signed by me this 28th day of February, 1874.

HENRY BERGER.
